UNITED STATES PATENT OFFICE.

ROBERT W. PAIN, OF NEW YORK, N. Y., ASSIGNOR TO THE AEOLIAN COMPANY, OF SAME PLACE.

GUIDE FOR PIANOLAS.

SPECIFICATION forming part of Letters Patent No. 630,558, dated August 8, 1899.

Application filed February 4, 1899. Serial No. 704,506. (No model.)

To all whom it may concern:

Be it known that I, ROBERT W. PAIN, a citizen of the United States, residing in the city of New York, borough of Manhattan, county 5 and State of New York, have invented a certain new and useful Guide for Pianolas, of which the following is a specification.

My invention relates to a guide for positioning an automatic playing device known as a 10 "pianola" belonging to a piano and for preventing relative movement between the two when the pianola is in operation.

I will describe a guide embodying my invention and then point out the novel features 15 thereof in the claims.

In the accompanying drawings, Figure 1 is a top view of a piano and a pianola in playing position before the piano and of guides embodying my invention. Fig. 2 is an enlarged top view of a guide embodying my invention. Figs. 3 and 4 are each detail views 20 of parts of the guide.

Similar letters of reference refer to corresponding parts throughout the several figures.

A represents a keyboard of a piano, and B a device, such as a pianola, for automatically operating the keys of the piano. The device B is separate from the piano, and when 30 not in use it may be moved away from it. In bringing the pianola in position before the keyboard it is necessary that the playing-fingers of the pianola be accurately placed over the proper keys and the pianola held in 35 this position while it is being operated. This may be done by means of guides C C, placed at each end of the pianola, one part of each guide being secured to the piano-casing and the other part to the pianola. Each guide is 40 made up of two parts c c'. The part c comprises an attaching-piece c², provided with slots c³, which permit of its adjustment, and an arm c⁴, that is hinged at one end to the attaching-piece c². The arm c⁴ is provided with 45 an adjusting-screw c⁵, against which the second part c' of the guide bears. This screw is for the purpose of holding the pianola away from the keyboard, so that its fingers will be in proper position over the keys. The arm 50 c⁴ is also provided with a curved surface c⁶,

which serves to guide the part c' into engagement with the adjusting-screw. The part c is secured to the under side of the keyboard-bed. The part c' of the guide is preferably secured to the pianola and comprises an attaching-plate c⁷ and a head c⁸, which engages with the screw c⁵.

When the pianola is not in use, the arms c⁴ of the guides are turned inward under the key-bed of the piano, as shown in dotted lines, 60 Fig. 2, so as to be out of the way.

What I claim as my invention is—

1. A guide for positioning an automatic playing device before the keys of a piano comprising two parts, one of which is secured to 65 the piano so as to be adjustable thereon longitudinally of the keyboard, and the other of which is secured to the automatic playing device and is adapted to bear against the part carried by the piano.

2. A guide for positioning an automatic playing device before the keys of a piano, comprising two parts: one of said parts consisting of an attaching-base, an arm hinged to said base, and the other of said parts consisting of a piece which bears against the said arm.

3. A guide for positioning an automatic playing device before the keys of a piano comprising two parts; one of said parts consisting of an attaching-base, an arm hinged to 80 said base, and the other part consisting of an attaching-piece and a head which engages with said arm.

4. A guide for positioning an automatic 85 playing device before the keys of a piano, comprising two parts, one of said parts consisting of an attaching-base, an arm hinged thereto, and an adjustable screw which is carried by said arm, and the other part consisting of 90 an attaching-piece and a head which engages said screw.

In testimony whereof I have signed my name to this specification in the presence of two subscribing witnesses.

ROBERT W. PAIN.
